FOREIGN PATENT DOCUMENTS

WO 2015/061425 A1 4/2015

Primary Examiner — Austin Murphy(74) *Attorney, Agent, or Firm* — Quarles & Brady LLP(57) **CLAIM**

The ornamental design for a hydraulic tool, as shown and described.

DESCRIPTION

FIG. 1 is an isometric view of a top, rear, and left side of another ornamental design for a hydraulic tool;

FIG. 2 is a front elevational view of the hydraulic tool of FIG. 1;

FIG. 3 is a rear elevational view of the hydraulic tool of FIG. 1;

FIG. 4 is a left side elevational view of the hydraulic tool of FIG. 1;

FIG. 5 is a right side elevational view of the hydraulic tool of FIG. 1;

FIG. 6 is a top plan view of the hydraulic tool of FIG. 1; and, FIG. 7 is a bottom plan view of the hydraulic tool of FIG. 1.
